UNITED STATES PATENT OFFICE.

CHARLES W. STICKLER, OF LANSFORD, PENNSYLVANIA.

SAFETY-LOCK FOR DUMP-CARS.

1,225,523.

Specification of Letters Patent.

Patented May 8, 1917.

Application filed April 1, 1916. Serial No. 88,332.

To all whom it may concern:

Be it known that I, CHARLES W. STICKLER, a citizen of the United States, residing at Lansford, in the county of Carbon and State of Pennsylvania, have invented new and useful Improvements in Safety-Locks for Dump-Cars, of which the following is a specification.

My present invention relates to improvements in dump cars or other vehicles wherein the body is adapted to be tipped or tilted to dump the load therefrom, and it relates more particularly to cars which are adapted to be tipped or tilted at the end or at some other portion of a track, tipples being commonly used in coal mining and other operations for tilting cars to dump the loads therefrom.

The primary object of the invention is to provide a safety latch which will operate with certainty to prevent unlocking of the dumping gate of the car while the car is in transit and which latch will be releasable to permit unlocking and opening of the gate when the load is to be dumped, the latch being preferably released automatically by the tipple bumper or any other suitable obstruction or projection when the car is brought into position where the load therein is to be dumped.

To these and other ends, the invention consists in certain improvements, and combinations and arrangements of parts, all as will be hereinafter more fully described, the novel features being pointed out particularly in the claims at the end of the specification.

In the accompanying drawing:—

Figure 1 is an elevation of one end of a dump car equipped with a safety latch embodying the present invention, the latch being shown by the full lines in locked position and by the dotted lines in unlocked position.

Fig. 2 represents an end view of the car as viewed from the right in Fig. 1.

Fig. 3 shows a portion of the car in dumping position.

Fig. 4 represents a section on the line 4—4 of Fig. 2.

Similar parts are designated by the same reference characters in the several views.

The present invention is applicable generally to dump cars or other vehicles wherein the body containing the load is adapted to be tipped or tilted to discharge the load therefrom, the load being normally retained

within the car when the latter is in a level position by a gate which is usually in the end of the car, and suitable catches are provided for holding the gate in closed position. 60 Preferably, and as shown, the invention is used in connection with a dump car provided with a dumping gate constructed in accordance with that shown in my prior Patent, No. 1,105,464, granted July 28, 1914. 65 While the invention is preferably used in connection with a dumping gate of that character, it is to be understood that the invention is not restricted to a dumping gate of this particular type, as the invention is 70 applicable to dumping gates of equivalent or similar construction.

In the present instance, 1 designates a portion of the body of the car, 2 the wheels which support the same to travel on a track 75 or other roadway, and a gate 3 serves to close one end of the body of the car, this gate when opened permitting the contents of the car to be dumped. In the present instance, the gate is provided at or near its 80 upper end with a pivot or gate rod 4 which extends through the upper portion of the gate and has its ends arranged to operate in rearwardly and upwardly inclined slots 5 which are formed in castings or members 85 6 fastened to the upper rear corners of the sides of the car body. Suitable means is also provided for holding the lower portion of the gate in closed position, such holding means being releasable, when the 90 car body is tilted, to discharge the contents of the car. The means for holding the lower portion of the gate in closed position comprises, in the present instance, a detent 95 7 which is fixed at each side of the car body, and a pair of bars or catches 8 which latter are pivoted on the gate at 9 and are guided toward their outer ends by cleats 10 whereby the outer or free ends of the bars 8 may have a limited vertical movement 100 relatively to the gate. The outer ends of the bars or catches 8 are adapted to rest in the notches or recesses 11 of the detents when the gate is in closed position, outward swinging of the lower portion of the gate 105 being then prevented. The detents 7 also preferably have inclines 12 leading to the recesses or notches 11 to lift the bars or catches 8 as the gate swings into closed position, whereby the bars or catches acting 110 as latches will reengage and become locked by the detents.

In coal mining and other operations, dump cars are used for handling coal or other material, and these cars are conveyed along the tracks to points where the loads in the cars are to be dumped. It is also common to employ in such connections tipples or tilttable platforms which are located at the dumping points, the car passing upon these tipples or tilting platforms whereupon the car is tilted by tipping of the tipple and the load is thereby discharged from the car. In the present instance, a portion of a tipple 13 is shown, the tipple having at the end of each rail a horn, bumper or obstruction 14 with which the wheels of the car engage whereby the motion of the car is arrested.

In dumping a car having a gate constructed as hereinbefore described, the longitudinal tilting of the car, due to rocking of the tipple, causes the load within the car body to press against the gate from the inside thereof. This pressure acting on the upper portion of the gate causes the same to move outwardly, and owing to the engagement of the pivot pins 4 on the gate in the upwardly and outwardly inclined slots 5 in the members 6, the gate will be lifted. Lifting of the gate will cause the lower ends of the cleats 10 which bear against the under sides of the bars or catches 8 to lift the catches out of the notches or recesses 11 in the detents, and the lower portion of the gate is then free to swing outwardly to permit discharge of the load from the car, as indicated in Fig. 3. When the car is restored to its normal or horizontal position, the gate swings by gravity into closed position about its pivots 4 as a center, and the bars or catches 8 will automatically become latched with the detents 7.

It is desirable, however, to provide means for preventing disengagement of the gate-holding catches from the detents during transit of the car. The present invention provides a simple and efficient device for accomplishing this purpose, and in its preferred form this device is capable of acting automatically to unlock the gate-holding catches when the car is brought to the dumping point. The safety locking device just described may be constructed in various ways. In the present instance, it comprises a sliding bar 15, one of these being provided to reciprocate on each side of the car body so as to assume a position above the respective bar or catch 8 to lock the same with its respective detent 7 or to clear the top of the bar or catch 8 and thereby permit release of the same from its detent. In the present instance, a lever 16 is provided for actuating each sliding bar 15, each lever being pivoted at 17 on a support 18 fastened to the respective side of the car, and the lower end of each lever 16 has an inturned end 19 which provides an operating projection arranged

in front of the respective car wheel and in a position to be engaged by the horn 14 of the tipple or by an equivalent part which serves to actuate it. A stationary guide 20 may be secured to each side of the car to guide the respective levers 16, and each of these levers and its coöperating parts may be covered by a casing or guard plate 21. The lower end of each lever 16 may further be guided by a plate 22 secured to the respective sides of the car frame. In a construction such as that just described, the levers 16 will normally hang by gravity in a nearly vertical position from their pivots 17, the locking bars 15 connected to these levers then occupying the positions above the catches 8 and hence the catches will be positively locked in engagement with the detents 7. The parts are in this position during transit of the car, and accidental unfastening and opening of the gate is effectually prevented. When, however, the car reaches the dumping point, the levers 16 are swung toward the car wheels 2, thereby withdrawing the bars 15 from above the catches 8 and the latter may then be disengaged from their detents 7. Preferably, the operating portions 19 of the levers 16 are located in such positions that, as the car is brought into the dumping position, these operating portions will be engaged by the horns 14 of the tipple or by some other suitable obstruction, the continued movement of the car causing the levers 16 to be swung toward the wheels 2, whereby the bars 15 will be withdrawn automatically from above the catches 8. Tilting of the car, which immediately follows, causes the catches to be unfastened and the gate opened in the manner hereinbefore described. After the load has been dumped, the car is returned to its level position, the catches are reengaged with the detents, and as the car is moved away from the horns 14, the levers 16 are permitted to swing by gravity toward their vertical position, the bars 15 being then automatically shifted into position to lock the catches 8 from disengagement relatively to their detents.

I claim as my invention:

1. In a dump car having an upwardly movable gate for unloading it, and a catch projecting laterally from and movable with the gate for holding the gate in its lower closed position, said catch being releasable to unfasten the gate by upward movement of the gate, a device coöoperative with the catch to lock the gate in its lower closed position during transit of the car and having a pendant portion normally holding said device in locking position and adapted to be actuated by an obstruction or projection to retract said device and thereby automatically unlock the catch and permit upward movement thereof and of the gate as the car is brought to the dumping point.

2. In a dump car adapted to be used in connection with a tipple, the combination of a gate for unloading the contents of the car, a catch carried by the gate for holding the latter in closed position, the gate and catch being movable downwardly and upwardly to fastened and unfastened positions respectively, and a horizontally slideable bolt movable into a position above the catch to lock the same and the gate in their lowered fastened position during transit of the car, said bolt having a lever pendant therefrom and in position to engage a part of the tipple to automatically unlock the catch as the car is brought to the dumping point.
3. In a dump car having a gate for dumping the contents thereof, and a catch for holding the gate in closed position, the gate and catch being movable downwardly and upwardly to fastened and unfastened positions respectively, a latch movable into a position above the catch to lock the same in gate-holding position during the transit of the car, and means for retracting said latch to unlock the catch when the car is brought to the dumping point, said latch having means for automatically moving it into a position to lock the catch as the latter is returned to gate-holding position.
4. In a dump car having a gate for unloading the same and a catch for holding the gate in closed position, the gate and catch

being movable vertically into fastened and unfastened positions, a device operative to lock the catch in gate-holding position during transit of the car, said device having a member movable into a position above the catch to retain the latter in gate-fastening position and also a coöperating part movable in a direction longitudinally of the car and adapted to engage a projection as the car is brought to the dumping point, thereby automatically unlocking the catch.

5. In a dump car, a load discharging gate pivotally mounted thereon, means for holding the lower portion of the gate in closed position embodying a detent fixed on the body of the car and a catch carried by and having a limited vertical movement relatively to the gate and adapted to coöperate with the detent, and means operative by the pressure of the load against the gate for lifting the latter and said catch and thereby disengaging the catch from said detent, said catch being movable vertically independently of the gate to reengage with said detent.

In testimony whereof I have hereunto set my hand in presence of two subscribing witnesses.

CHARLES W. STICKLER.
